CLIP FOR A WRITING INSTRUMENT

Robert J. Burnham, 179—39 Tudor Road,
Jamaica Estates, N.Y.

Filed Mar. 28, 1960, Ser. No. 59,888

Term of patent 14 years

(Cl. D74—2)

Fig. 1

Fig. 2

Fig. 4

FIG. 1 is a front elevational view of a clip for a writing instrument showing my new design; parts of a writing instrument being shown in broken lines for illustrative purposes;

FIG. 2 is a side elevational view thereof;

FIG. 3 is a front perspective view thereof; and

FIG. 4 is a cross section thereof taken on the line 4—4 of FIG. 1.

I claim:

The ornamental design for a clip for a writing instrument, as shown and described.
